Fig. 1

Fig. 2

FIG. 1 is a perspective view of a fishing rod holder showing my ornamental design in use and placed on the hull and gunwale of a boat. The boat and fishing rod placed in the holder as illustrated in FIG. 1, do not comprise any portion of the ornamental design;

FIG. 2 is an enlarged perspective view of the fishing rod holder illustrated in FIG. 1;

FIG. 3 is a top plan view of FIG. 2;

FIG. 4 is a side elevational view of FIG. 2, it being understood that the opposite side is a mirror image thereof;

FIG. 5 is an end elevational view of FIG. 2;

FIG. 6 is a bottom plan view of FIG. 2; and FIG. 7 is a front elevational view of FIG. 2.

I claim:

The ornamental design for a fishing rod holder, as shown and described.
